V. WILLOUGHBY

CAM BRAKE SHEAVE AND SUPPORT

Filed Feb. 1, 1924

Fig. 1.

UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

CAM-BRAKE SHEAVE AND SUPPORT.

Application filed February 1, 1924. Serial No. 689,898.

To all whom it may concern:

Be it known that I, VICTOR WILLOUGHBY, residing at Ridgewood, Bergen County, State of New Jersey, and being a citizen of the United States, have invented certain new and useful Improvements in a Cam-Brake Sheave and Support, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Fig. 1 is a vertical longitudinal section of one end of a hopper car provided with a brake sheave and support constructed in accordance with this invention;

Fig. 2 is a fragmentary front elevation showing the cam brake sheave and support as applied in Fig. 1;

Fig. 3 is a section taken on the line 3—3 of Fig. 1; and

Fig. 4 is a horizontal section taken on the line 4—4 of Fig. 1, the car frame and the plate which supports the brake lever being indicated by broken lines.

It is an object of this invention to provide an improved cam brake sheave and support particularly adapted for hopper cars, but which may be readily applied to other types of cars.

In the drawings, this invention is shown applied to a hopper car having an end sill 1 and a center sill 2 which support the usual hopper body comprising an end sheet 3 and a slope floor sheet 4, the end sheet 3 being connected to the end sill 1 by angle members 5. Secured to the center sill 2 by the rivets 6, which secure the center sill cover plate 7 thereto, is a plate 8 connected to the end sill 1 by means of an angle 9. The plate 8 is slotted as at 10 and has secured to its underside, adjacent to the slot, angle members 11 and 12 having pivotally mounted therein a brake lever 13 to which is connected a brake cylinder rod 14 and a brake rod 15.

Secured to the plate 8 and to the end sill

1 is a bent supporting member 16 to which is secured an inverted U-shaped member 17 which has its web 18 connected to the supporting member 16 by rivets 19 and is provided with an outwardly projecting flange 60 20 which is secured to the lower flange of the center sill 2 by rivets 21. The U-shaped member 18 has its sides 22 and 23 provided with openings in which is mounted a pin 24 which rotatably supports a cam brake sheave 65 25. The sides 22 and 23 of the U-shaped member 17 are connected by the bent member 26 which has its ends secured to the sides of the member 17 and provided with openings to receive the pin 24 and has its 70 center portion 27 bent to serve as a brake mast step for the brake mast 28 which has its lower end of reduced diameter passing through an opening in the portion 27. The 75 brake mast 28 is guided in openings in the supporting member 16, in the brake step 29 and in the bracket 30 carried by the angle member 31 at the upper edge of the hopper end sheet 3. The brake mast is provided with the usual pawl and ratchet 32 and 80 hand wheel 33 and the brake step 29 is supported on brackets 34 secured to the hopper end sheet 3 and to the angle members 5.

The cam sheave 25 is provided with a substantially semi-cylindrical portion 35 85 having a groove 36 therein in which engages a chain 37 which has one end secured to the brake mast and its other end secured in the groove as at 38. The cam brake sheave 25 is also provided with a hook 39 to which is 90 secured a chain 40 which has its other end secured to the brake lever 13 as at 41.

In the operation of this device, rotation of the brake mast 28 to apply the brakes will cause rotation of the cam sheave 25, it being noted that as the chain 37 is wrapped about the brake mast 28 the effective radius through which power is applied to the cam brake sheave 25 gradually increases to a maximum and thereafter remains constant, whereas the effective radius through which power is applied by the cam brake sheave through the hook 29 to the chain 40 gradually decreases from a maximum to a minimum, and thereupon remains constant as 100 the chain 40 is wrapped about a drum 42 formed at the hub of the cam brake sheave.

What is claimed is:

1. In a car having center and end sills, a car brake comprising a cam brake sheave 110

- operatively connected to the brake lever, an inverted U-shaped member supporting said cam brake sheave and having a projection connected to said center sill and supporting means for said U-shaped member supported from said center and end sills.
2. In a car brake, a cam brake sheave operatively connected to the brake lever, an inverted U-shaped member supporting said cam brake sheave, a brake mast operatively connected to said cam brake sheave, a brake mast step connecting the sides of said U-shaped member, and supporting means for said U-shaped member adapted to guide said brake mast.
3. In a car having center and end sills, a car brake comprising a cam brake sheave operatively connected to the brake lever, a U-shaped member supporting said cam brake sheave, a brake mast operatively connected to said cam brake sheave, a brake mast step serving as a strut between said brake mast and said U-shaped member and means supported from said sills supporting said U-shaped member and adapted to guide said brake mast.
4. In a car having center and end sills, a car brake comprising a cam brake sheave operatively connected to the brake lever, an inverted U-shaped member supporting said cam brake sheave and connected to said center sill, a brake mast operatively connected to said cam brake sheave, a brake mast step adapted to serve as a strut between said brake mast and said U-shaped member
- and a support for said U-shaped member connected to said end sill and adapted to guide said brake mast.
5. In a car having center and end sills, a car brake comprising a cam brake sheave operatively connected to the brake lever, an inverted U-shaped member supporting said cam brake sheave and connected to said center sill, a brake mast operatively connected to said cam brake sheave, a brake mast step connecting the sides of said U-shaped member and serving as a strut between said brake mast and said U-shaped member and supporting means for said U-shaped member. 50
6. In a car having center and end sills, a car brake comprising a cam brake sheave operatively connected to the brake lever, a U-shaped member supporting said cam brake sheave and connected to said center sill, a brake mast operatively connected to said cam brake sheave, a brake mast step connecting the sides of said U-shaped member and serving as a strut between said brake mast and said U-shaped member and supporting means for said U-shaped member connected to said end sill and adapted to guide said brake mast. 55

In witness whereof I have hereunto set my hand in the presence of two witnesses.

VICTOR WILLOUGHBY.

Witnesses:

F. HARING,
R. W. SMITH.
